DESIGN FOR A SLIPPER

Harvey B. Evans, Wakefield, Mass.

Application December 29, 1938, Serial No. 82,061

Term of patent 7 years

To all whom it may concern:

Be it known that I, Harvey B. Evans, a citizen of the United States, residing at Wakefield, in the county of Middlesex and State of Massachusetts, have invented a new, original, and ornamental Design for a Slipper, of which the following is a specification, reference being had to the accompanying drawing, forming part thereof.

The design is characterized by the configuration of the U-shaped moccasin seam, the sides of which extend in the general direction of the top of the counter terminating in a substantially V-shaped indentation on each side in the edge of the foot opening.

I claim:

The ornamental design for a slipper, as shown and described.

HARVEY B. EVANS.
